MAGNETIC FREQUENCY DIVIDER

Harold J. McCreary, Lombard, Ill., assignor to
 Automatic Electric Laboratories, Inc., Chicago,
 Ill., a corporation of Delaware

Application June 21, 1950, Serial No. 169,489

11 Claims. (Cl. 321—68)

1

This invention relates in general to frequency changers, and more particularly to a means for deriving current of one frequency from a source of current of a different frequency.

An object of the present invention is to provide a sub-frequency generator of the magnetic cross valve type having an improved load regulation characteristic by controlling the direct current magnetization at the center of the cross valve core.

Another object of the present invention is to provide a sub-frequency generator of the magnetic cross valve type having self-starting characteristics by providing a continuous pulsating magnetizing current.

A feature of the present invention is the use of a cross-coil on a generator of the cross valve type having a continuous pulsating current flowing therein.

Another feature of the present invention is the use of an electrolytic condenser as a D. C. input feed to the cross winding to improve the self-starting and load regulation characteristics.

Other objects of the invention will appear upon a further perusal of the specification taken in conjunction with the accompanying drawings which illustrate several of the embodiments of the invention in the form of schematic diagrams.

Fig. 1 is a diagrammatic representation of a magnetic cross valve sub-frequency generator utilizing a direct current so as to excite a resonant circuit to provide a continuous pulsating current in the cross winding.

Fig. 2 is a diagrammatic representation of a magnetic cross valve sub-frequency generator having a winding coupled to the input winding and the current flowing therefrom rectified to provide a continuous pulsating current for the cross winding.

Fig. 3 is a graphical illustration of the load regulation for Fig. 2.

Fig. 4 is a diagrammatic representation of a magnetic cross valve sub-frequency generator using permanent magnets to provide a biasing flux at the center of the magnetic cross valve core.

Fig. 5 shows a diagrammatic representation of a magnetic cross valve sub-frequency generator in which the leg coils produce a biasing flux by rectifying the input signal.

Fig. 6 is a diagrammatic representation of a magnetic cross valve sub-frequency generator having a biasing flux produced by using low voltage rectifiers on the leg coils.

In the magnetic cross valve systems of the type

2

herein used two windings are displaced by 90 degrees so as to provide that the mutual inductance between the respective windings is substantially zero at partial saturation, but which induces odd harmonics in the secondary winding at high degrees of saturation.

In the present invention cross coils are energized by continuous pulsating current which provides a D. C. flux to bias the cross valve core to a point close to saturation and thereby provides a self-starting system. The frequency of the cross coil added to the frequency of the secondary winding will equal the input signal. The oscillating frequency of the cross coil is caused by a flux differential between the D. C. saturating flux and the flux produced by the input signal. The oscillating frequency for the output winding is provided by the saturating flux and the flux produced by the oscillation of the cross coil. In some instances a permanent magnet is used to provide the saturating flux and the cross coil will provide an alternating current to produce an alternating flux which is superimposed on the D. C. flux produced by the permanent magnets.

Referring now to Fig. 1, the cross valve 5 herein used may be of the type shown in Patent No. 2,455,078, issued on November 30, 1948, to the present inventor, Patent No. 2,461,992, issued on February 15, 1949, to the present inventor and Patent No. 2,445,857, issued on July 27, 1948, to the present inventor. The cross valve 5 has two intersecting members. A primary coil 7 is wound through a pair of diagonal corners of the intersection. Serially connected to the primary winding 7 are two auxiliary windings 8 and 9. An input signal which may be 130 volts 60 cycles is used to energize the primary winding 7 and the auxiliary windings 8 and 9. The auxiliary windings 8 and 9 are wound around the two different intersecting members of the cross valve 5. A cross winding 6 is wound through the other diagonal corners of the intersection so as to be displaced 90 degrees from the primary winding. A battery 1 is used to energize the resonating circuit of the cross winding 6. The resonating circuit comprises inductance coil 2, condenser 3 and cross winding 6. A secondary winding from which the output signal is produced comprises two serially connected coils 10 and 11. Coil 10 is wound around one of the intersecting members of the cross valve 5 and the coil 11 is wound around the other intersecting member of the cross valve 5. The output is taken from the secondary winding across the condenser 12. The oscillating circuit for the secondary winding comprises condenser

12 and coils 10 and 11. In more detail, a 60 cycle input signal energizes the auxiliary windings 9 and 8 and the primary winding 7. Concurrently, the battery 1 energizes the resonant circuit comprising inductance choke 2, condenser 3, and the cross winding 6. As a result thereof a continuous pulsating flux is produced through the intersecting legs of the cross valve 5 by the current flow through the cross winding 6. A D. C. saturating flux is thereby produced. In response to the cross valve core 5 reaching the point of saturation which is produced by the D. C. biasing flux, the secondary circuit comprising the windings 10 and 11 and condenser 12 will oscillate at the desired frequency. The secondary circuit is tuned to the desired sub-frequency which in this instance is 20 cycles. The current flow in the coils 10 and 11 is produced by a flux differential of the pulsating flux produced by the cross winding 6. The current flow in the cross winding 6 is an alternating current superimposed on a direct current. The output frequency plus the alternating frequency of the cross winding is equal to the input frequency.

Referring now to Fig. 2 an input signal source is provided to energize the primary winding 17 and the auxiliary windings 18 and 19. The cross valve 13 herein used may again be of the type disclosed in the previously mentioned patents to the present inventor. The cross valve herein used has two intersecting members. A primary coil 17 is wound through two opposite diagonal corners of the intersection and is serially connected to two auxiliary windings 18 and 19. The auxiliary winding 18 is wound around one intersecting member, while the other auxiliary coil 19 is wound around the other intersecting member. A power supply providing 130 volts at 60 cycles is used to energize the windings 17, 18 and 19. A cross winding 20 is wound around the other diagonal corners of the intersection so as to be displaced 90 degrees from the primary winding 17. An additional winding 70 is wound through the same diagonal corners of the intersection as is wound the primary winding 17 and is inductively coupled to the primary winding. The additional winding 70 is connected to a pair of opposite junctions of the bridge rectifier comprising rectifiers 24, 25, 26 and 27. At the opposite junctions from which the additional winding 70 is connected, a 500 mf. electrolytic condenser 23 is connected to the bridge rectifier. In parallel with the electrolytic condenser 23 is connected an oscillating circuit comprising inductance coil 22, condenser 21 and cross coil 20. The output circuit comprises the secondary windings 15 and 16 and the condenser 14. The secondary winding 15 is wound around one leg of the cross valve 13 at a point opposite that from which the auxiliary winding 18 is wound. The other secondary winding 16 is wound around the other intersecting member of the cross valve 13 at a point opposite that from which the auxiliary winding 19 is wound. The secondary windings 15 and 16 and the condenser 14 are tuned to the desired output frequency, which in this instance is 20 cycles. The auxiliary windings 18 and 19 may have seventy-five turns each whereas the primary winding 17 may have one hundred-fifty. The additional winding 70 may have fourteen turns and the cross winding 20 may have five hundred turns. The condenser 21 may be a 30 mf. condenser. The secondary windings 16 and 15 may each have five hundred turns. Condenser 14 may be a 12 mf. condenser. The output frequency under the present conditions

will be a 20 cycle signal at 80 volts. In more detail, the power supply energizes the auxiliary windings 18 and 19 and the serially connected primary winding 17 and thereupon the additional winding 70 is energized by magnetic coupling between the primary winding 17 and the additional winding 70. The frequency of the induced current in additional winding 70 is 60 cycles which is the same frequency as the primary winding. The current flow in the additional winding 70 provides a D. C. current feed to the cross coil 20 over the following paths: additional winding 70, rectifier 26, choke 22, cross winding 20, rectifier 24 and the other end of additional winding 70. The other path for the alternating current flow is as follows: additional winding 70, rectifier 27, choke 22, cross winding 20, rectifier 25 and the other end of additional winding 70. Current flow for the additional winding 70 is rectified to charge the condenser 23 in the following manner: additional winding 70, rectifier 26, condenser 23, rectifier 24 to the other end of the additional winding 70 and the return path for the alternating current for additional winding 70 is as follows: additional winding 70, rectifier 27, condenser 23, rectifier 25 and back to the additional winding 70. The D. C. voltage produced in condenser 23 is used to aid the load regulation characteristics. The inductance coil 22 is used for damping the ripples produced in the rectifying process. The circuit including condenser 21 and cross winding 20 is tuned to oscillate at 40 cycles. The direct current fed to the cross winding 20 provides a pulsating current. The pulsating current comprises an alternating current superimposed on a direct current. As a result thereof, a D. C. flux is produced in the intersecting members to provide a saturating or biasing flux. A differential flux produced by the D. C. saturating flux and the alternating flux of cross winding 70 induces an alternating current signal in the secondary windings 15 and 16. The resonating circuit comprising condenser 14 and secondary windings 15 and 16 is tuned for 20 cycle signal.

Referring now to Fig. 3 which is a graphical illustration of the load regulation of the system shown in Fig. 2. The horizontal axis illustrates the output current in milliamperes at 20 cycles. The vertical axis illustrates the output volts at 20 cycles.

Referring now to Fig. 4 which is a schematic diagram showing how the present invention can be used, omitting the choke, electrolytic condenser and the additional secondary windings which were used for Fig. 2. The cross valve 28 herein used may again be of the type disclosed in the previously mentioned patents. The cross valve has two intersecting members. An air gap is shown in Fig. 4 at two points alternately opposite the horizontal intersecting member. Permanent magnet 30 is shown extending from the horizontal intersecting member to the top of the cross valve. Another permanent magnet 29 is shown extending from the other end of the horizontal intersecting member to the bottom of the cross valve 28. The primary winding 36 is wound through opposite diagonal corners of the intersecting members. Serially connected to the primary winding 36 are two additional windings 37 and 38. Winding 38 is wound around one intersecting member and winding 37 is wound around the other intersecting member. The power supply providing 130 volts at 60 cycles energizes the primary winding 36 and the two additional windings 37 and 38. Cross winding 35

is wound through the other diagonal corners of the intersection of the cross valve 28. The cross winding 35 is displaced 90 degrees from the primary winding 36. Condenser 31 is connected to the cross winding 35 to provide a resonant circuit. The output circuit comprises two secondary windings 33 and 34 and the condenser 32. The winding 33 is wound around the same intersecting member as in the additional winding 37 but at an opposite point. The secondary winding 34 is wound around the same intersecting member as is additional winding 38 but at an opposite point. The output circuit comprising condenser 32 and secondary windings 33 and 34 is tuned to the output frequency at 20 cycles. In more detail, a 130 volt 60 cycle power supply energizes the additional windings 37 and 38 and the primary winding 36. The permanent magnets 30 and 29 produce a D. C. saturating flux in the core of the cross valve 28. The differential flux produced by the D. C. saturating flux and the alternating flux produced by the primary winding 36 induces a voltage in the resonating circuit comprising the cross coil 35 and the condenser 31. The circuit including cross coil 35 and the condenser 31 is tuned to 40 cycles. It is to be noted that there is no mutual inductance between the coil 35 and the coil 36, until the magnetic core 28 has reached a point of near saturation which is produced by the D. C. magnetizing flux.

A voltage is now produced in the secondary windings 33 and 34 of the output circuit. The induced voltage is produced by a flux differential caused by the D. C. saturating flux produced by the permanent magnets 30 and 29 and the alternating flux produced by the winding 35. As a result thereof a 20 cycle voltage is induced in the windings 33 and 34, since a resonating circuit comprising these respective windings and the condenser 32 is tuned for that frequency. The 20 cycle frequency of the output winding plus the 40 cycle frequency of the cross winding equals the 60 cycle input frequency of the primary winding.

Referring now to Fig. 5, a cross valve 39 herein used may be of the type disclosed in the previously mentioned patents. The cross valve has two intersecting members forming two pairs of diagonally opposite corners. A primary winding 44 is wound diagonally through two corners of the intersection. Serially connected to the primary winding 44 are two auxiliary windings 41 and 46. The power supply providing 130 volts at 60 cycles energizes the primary winding 44 and the auxiliary windings 46 and 47. In parallel with the auxiliary winding 47 is a rectifying circuit comprising inductance coil 48, condenser 50 and rectifier 53. In parallel with the auxiliary winding 46 is another rectifying circuit comprising inductance coil 49, condenser 51, and rectifier 52. A cross winding 45 is wound around the other diagonal corners of the intersection of the cross valve 39. Condenser 41 is connected to the cross winding to provide a resonating circuit. The output circuit comprises condenser 40 and secondary windings 42 and 43. Secondary winding 42 is wound around the same intersecting member as is auxiliary winding 46, but at an opposite end. Secondary winding 43 is wound around the same intersecting member as is auxiliary winding 47, but at an opposite end. The condenser 40 provides a resonating circuit with the secondary windings 42 and 43 to oscillate at 20 cycles. In more detail, the 130 volt 60 cycle power supply energizes the primary winding 44 and the auxiliary windings 41 and 46 over the following path:

power supply, auxiliary winding 47, primary windings 44, auxiliary winding 46 and back to the power supply. A direct current is produced in the auxiliary winding 47 by the rectifying circuit over the following path: rectifier 53, auxiliary winding 47, inductance coil 48 and back to the rectifier 53. In a similar manner direct current is produced in the auxiliary winding 46 over the following path: rectifier 52, inductance coil 51, auxiliary winding 46 and back to the rectifier 52. The rectified current in the auxiliary coils 47 and 46 produces D. C. magnetizing fluxes which are opposing one another. As a result thereof, voltage is induced in the cross winding 45 by a differential flux produced by the flux of the primary winding of the coil 44 and the D. C. saturating flux produced by the auxiliary windings 46 and 47. The circuit comprising the cross coil 45 and condenser 41 oscillates at 40 cycles.

A voltage is now induced in the secondary windings 42 and 43 which is caused by a differential flux. This differential flux is produced by the D. C. saturating flux provided by the auxiliary windings 47 and 46 and alternating flux provided by the cross winding 45. The output circuit, comprising secondary windings 42 and 43 and condenser 40, oscillates at the tuned frequency 20 cycles.

Referring now to Fig. 6 which is a schematic diagram showing how a D. C. field can be produced using a low voltage rectifier on the leg coils. Cross valve 54 herein used may be of the type disclosed in said previously mentioned patents. The cross valve has two intersecting members forming two pairs of opposite diagonal corners. An input winding 60 is wound through a pair of the opposite diagonal corners at the intersection. Serially connected to the primary winding 60 are two auxiliary windings 63 and 61. Auxiliary winding 63 is wound around one of the intersecting members, while winding 61 is wound around the other intersecting member. Saturating winding 64 is wound on the same intersecting member as is wound auxiliary winding 63. In a similar manner, the saturating winding 62 is wound around the same intersecting member as is wound the auxiliary winding 61. Additional winding 71 is wound through the same diagonal corners as is wound the primary winding 60. The primary winding 60 and the additional winding 71 are magnetically coupled. A circuit comprising rectifier 66, 67, 68, 69 and condenser 65 connects the saturating windings 64 and 62 with the additional winding 71. The cross winding 59 is wound through the other opposite diagonal corners of the intersection and is displaced 90 degrees from the primary winding 60. A condenser 56 forms an oscillating circuit with the cross winding 59 to oscillate at 40 cycles. The output circuit comprises secondary windings 57 and 58 and the condenser 55 and is tuned to 20 cycles. The secondary winding 57 is wound around the same intersecting member as is auxiliary winding 61, but at an opposite point. The secondary winding 58 is wound around the same intersecting member as is auxiliary winding 63, but at an opposite point. In more detail, the power supply providing 130 volts at 60 cycles energizes the auxiliary windings 63 and 61 and the primary winding 60. The additional winding 71 is magnetically coupled to the primary winding 60 and thereby a voltage is induced in the additional winding 71. As a result thereof, a rectified voltage is produced in the saturating windings 64

and 62 over the following path: additional winding 71, rectifier 69, saturating winding 64, saturating winding 62, rectifier 67 and back to the additional winding 71. The saturating windings 64 and 62 produce a D. C. saturating flux for the cross valve 54 thereby providing a biasing flux. Voltage is induced in the cross winding 59 by a differential flux produced by the D. C. saturating flux and an alternating flux. The D. C. saturating flux which is a biasing flux is produced by the windings 64 and 62. The alternating current flux is produced by the windings 62, 63 and 60. Since the cross winding 59 is tuned to 40 cycles by the condenser 56, that circuit will oscillate at the desired frequency. As a result thereof, voltage is induced in the secondary windings 57 and 58 which is caused by a differential flux. The differential flux is produced by the D. C. magnetizing flux and the alternating current flow. The last mentioned D. C. saturating flux is provided by the saturating windings 64 and 62 and the alternating current flux is produced by the cross winding 59. Since the condenser 55 is tuned with the secondary windings 57 and 58, to oscillate at 20 cycles, the output frequency derived from this system is a 20 cycle signal.

Although I have described my invention with a certain degree of particularity it should be understood that the present disclosure has been made only by way of example and that numerous changes in the details of construction and the completion and arrangement of parts may be resorted to without departing from the true spirit and scope of the invention as hereinafter claimed.

What is claimed is:

1. In a static frequency changer, a saturable magnetic core having a pair of intersecting members, a primary winding wound through one pair of diagonally opposite corners of the intersection, a secondary winding wound around said pair of intersecting members, a source of alternating current connected to said primary winding for providing an input signal, a load circuit connected to said secondary winding, a single cross winding wound through the other pair of diagonally opposite corners of said intersection, rectifier means for producing a direct current, resonating means for producing an alternating current of a frequency different from said input signal frequency, said resonating means including said single cross winding, means inductively coupled to said primary winding for supplying a current to said rectifier means connected to said single cross winding for producing a biasing flux in said magnetic core, said alternating current in said cross winding inducing a differential flux in said magnetic core, whereby alternating currents having a frequency integrally related to the frequency of said source is delivered to said load circuit.

2. In a static frequency changer, a saturable magnetic core having a pair of intersecting members, a primary winding wound through one pair of diagonally opposite corners of the intersection, a secondary winding wound around said pair of intersecting members, a source of alternating current connected to said primary winding for providing an input signal, a load circuit connected to said secondary winding, a source of direct current, a single cross winding wound through the other pair of diagonally opposite corners of said intersection and continuously energized by said source of direct current

5 for producing a biasing flux in said core, resonant circuit means including said cross winding inductively coupled to said source of alternating current for producing an alternating current in said cross winding in turn producing a differential flux in said core whereby alternating currents having a frequency integrally related to the frequency of said source of alternating current are delivered to said load circuit.

3. In a frequency changer, a magnetic core structure having two intersecting members, a primary circuit including a coil wound through a pair of diagonal corners of the intersection to provide the input signal, a secondary circuit including a condenser and a coil wound around the two intersecting members and tuned to the desired output signal, a source of current, said current connected to said primary circuit, a differential circuit including only one coil wound through the other pair of diagonal corners of the intersection, means connected to said source of current and said differential circuit for providing a continuous pulsating current in said differential circuit, said current in said coil in said differential circuit thereby inducing a continuous pulsating flux in said core whereby said pulsating current provides a flux for self-starting characteristics so that said secondary circuit oscillates at the tuned frequency in response to said flux in said magnetic core structure.

4. In a frequency changer, a magnetic core structure having two intersecting members, a primary circuit including a coil wound through a pair of diagonal corners of the intersection, a first source of current connected across said primary circuit for energizing said primary circuit to provide the input signal, a secondary circuit including a condenser and a coil wound around the two intersecting members and tuned to a desired output signal, a source of pulsating direct current, a resonant circuit connected thereto, a single cross winding wound through the other pair of diagonal corners of the intersection and forming part of said resonant circuit for providing continuous pulsating current, whereby said cross winding provides a biasing flux and a differential flux for said magnetic core structure so that said secondary circuit oscillates at the tuned frequency in response to said flux differential in said magnetic core structure, thereby providing self-starting characteristics.

5. In a frequency changer, a magnetic core structure having two intersecting members, a primary circuit including a coil wound through a pair of diagonal corners of the intersection to provide the input signal, a secondary circuit including a condenser and a coil wound around the two intersecting members and tuned to the desired output signal, an additional circuit including a coil wound through said pair of diagonal corners of the intersection and inductively coupled to said primary circuit for providing continuous oscillations, a differential winding having a condenser connected in parallel therewith wound through the other pair of diagonal corners of the intersection, rectifier means connected to said additional circuit for rectifying part of the input signal induced in said additional circuit, said differential winding connected to said additional winding for providing a continuous current in said differential winding in response to the continuous oscillations of said additional winding and said rectifier means for providing a biasing flux in said magnetic core structure, and means comprising said differential wind-

ing operated responsive to the input signal flux and the biasing flux for producing a differential flux in said core, whereby said secondary circuit oscillates at the tuned frequency in response to said flux differential and said biasing flux in said magnetic core structure, thereby providing self-starting characteristics.

6. In a frequency changer, a magnetic core structure having two intersecting members, a primary circuit including a coil wound through a pair of diagonal corners of the intersection to provide the input signal, a secondary circuit including a condenser and a coil wound around the two intersecting members and tuned to a desired output signal, an additional circuit including a coil wound through said pair of diagonal corners of the intersection inductively coupled to said primary circuit to provide continuous oscillations, a differential circuit including a condenser and a coil wound through the other pair of diagonal corners of the intersection, and a rectifier interconnecting said additional circuit and said differential circuit for rectifying part of said input signal induced in said additional circuit to provide a continuous current in said differential circuit in response to the continuous oscillations of said additional circuit for providing a biasing flux in said magnetic core structure, and means including said differential circuit operated responsive to the input signal flux and the biasing flux for producing a differential flux in said core, whereby said secondary circuit oscillates at the tuned frequency in response to said biasing flux and said differential flux to provide self-starting characteristics.

7. In a frequency changer as claimed in claim 6, and including an electrolytic condenser connected in parallel to said differential circuit and charged by the rectified current for improving the load regulation.

8. In a frequency changer, a magnetic core structure having two intersecting members, a source of alternating current, a primary circuit including a coil wound through a pair of diagonal corners of the intersection connected across said source of alternating current to provide the input signal in response to energization by said source of current, a secondary circuit including a condenser and a coil wound around the two intersecting members and tuned to a desired output signal, a source of direct current, a resonant circuit comprising a coil and a condenser tuned to a frequency which is the difference between said input signal frequency and said output signal frequency connected thereto, said last mentioned coil wound through the other pair of diagonal corners of the intersection, said resonant circuit operating responsive to said direct current and said input signal for providing continuous pulsating current whereby said last mentioned coil provides a biasing flux and a differential flux for said magnetic cross structure so that said secondary circuit oscillates at the tuned frequency in response to said flux differential in said magnetic core structure, thereby providing self-starting characteristics.

9. In a frequency changer, a magnetic core structure having two intersecting members, a primary circuit including a coil wound through a pair of diagonal corners of the intersection, a source of alternating current connected to said primary circuit to energize said primary circuit for providing the input signal whereby an input flux is induced in said core, a secondary circuit including a condenser and a coil wound around

the two intersecting members and tuned to the desired output signal, an additional winding wound around said pair of diagonal corners and inductively coupled to said primary circuit to provide continuous oscillations in said additional winding, a differential circuit including a condenser and a coil wound through the other pair of diagonal corners of the intersection, said last mentioned coil and condenser resonant to a frequency other than the input frequency, a bridge rectifier having two pairs of diagonal corners, one pair of diagonal corners of said rectifier connected to said additional circuit and the other pair of diagonal corners of said rectifier connected to said differential circuit whereby said differential circuit provides a continuous pulsating current in response to the rectification of said continuous oscillating current in said additional winding by said bridge rectifier and said input flux whereby said differential circuit provides a flux in said magnetic core structure so that said secondary circuit oscillates at the tuned frequency in response to flux in said magnetic core structure, thereby providing self-starting characteristics.

10. A frequency changer as claimed in claim 9, and including an electrolytic condenser connected to said other pair of diagonal corners of said rectifier, whereby said rectified current charges said electrolytic condenser to provide improved load regulation.

11. In a frequency changer, a saturable magnetic core having a pair of intersecting members, a primary winding wound through one pair of diagonally opposite corners of the intersection, a secondary winding wound around said pair of intersecting members, a resonant circuit resonant at a certain frequency and including said secondary winding, a source of alternating current connected to said primary winding for providing an input signal, the frequency of said source of alternating current being greater than the frequency of said resonant circuit, a load circuit connected to said secondary winding for providing an output signal, a single cross winding wound through the other pair of diagonally opposite corners of said intersection, a condenser connected across said single cross winding forming a circuit resonant at a frequency which is the difference between the aforementioned frequencies, and means comprising a direct current source connected across said single cross winding for producing a biasing flux in said magnetic core, and means comprising said last mentioned means, said source of alternating current, and said circuit including said cross winding and condenser for producing a differential flux in said magnetic core, whereby alternating currents having a frequency integrally related to the frequency of said source are delivered to said load circuit.
